BUTTON-HOLDING CHUCK.

1,332,817.

Specification of Letters Patent.

Patented Mar. 2, 1920.

Application filed October 17, 1919. Serial No. 331,338.

To all whom it may concern:

Be it known that we, PAUL F. DUSHA and ANTON FEYK, citizens of the United States, and residents, respectively, of the city of New York, borough of Manhattan, in the county and State of New York, and Bohemia, in the county of Suffolk and State of New York, have invented a new and Improved Button-Holding Chuck, of which 10 the following is a full, clear, and exact description.

This invention relates to chucks such as are employed for holding buttons in the manufacture of pearl buttons and has general reference to that type of devices shown 15 and claimed in Patent No. 943,616, issued to Holub-Dusha Co., on the 14th day of December, 1909, on application of Louis W. Holub.

20 Among the objects of this improvement is to simplify the means for adjusting and locking of the button supporting abutment member so as to render it unnecessary for the application of a tool into or through the 25 lower end of the spindle, the spindle being normally locked in place in the main portion of the machine in such a position as to render access thereto relatively difficult.

With the foregoing and other objects in 30 view the invention consists in the arrangement and combination of parts hereinafter described and claimed, and while the invention is not restricted to the exact details of construction disclosed or suggested herein, 35 still for the purpose of illustrating a practical embodiment thereof reference is had to the accompanying drawings, in which like reference characters designate the same parts in the several views, and in which—

40 Figure 1 is a vertical sectional view of our improved chuck in one operative position.

Fig. 2 is a side elevation of the abutment member and supporting quill.

Fig. 3 is a side elevation of the locking 45 plug and its extended stem; and

Fig. 4 is a plan view of the chuck as shown in Fig. 1.

50 Referring now more specifically to the drawings we show at 10 a tubular spindle having at its upper end a chuck socket 11, the walls of the socket being split vertically or longitudinally at 12 to provide ample flexibility therefor as is well known in this type of devices. The spindle is provided

with a central bore 13 having a threaded portion 13^a toward the lower end of the spindle and having an internally threaded counterbore 13^b reaching approximately to the lower end of the spindle.

The abutment member comprises a head 14 and a quill 15 constituting a stem for supporting the head. The head is provided with a transverse groove 16 and the lower end of the quill is externally threaded at 17 for coöperation with the threaded bore 13^a 65 whereby the position of the head may be suitably determined by the application of a screw driver or the like in the groove 16 through the open upper end of the chuck. The lower threaded end 17 of the quill is 70 preferably split longitudinally at 17^a and the extreme lower end thereof is beveled or reamed out at 18.

After the abutment is adjusted at the proper elevation in the manner above described it is locked firmly in such position by means of a plug 19 having a frusto-conical or tapered shoulder 20 and a stem 21. The plug 19 has threaded engagement in the counterbore 13^b of the spindle and the 80 tapered shoulder 20 projects into the reamed end 18 of the quill whereby the split end portion of the quill is spread apart causing the wedging or binding of the threaded portion 17 thereof in the bore 13^b. By reason, however, 85

of the threaded engagement of the plug in the counterbore 13^b the locking of the quill might be made complete even without the split 17^a and the reamed end 18. We prefer, however, 90 that the parts be made as indicated for the most satisfactory operation. The stem 21 extending upward through or practically through the bore of the quill and being provided at its upper end with a groove 22 may 95

easily be reached with a screw driver projected downward through the abutment head. It is, therefore, unnecessary to reach through the lower end of the spindle for any purpose, although for convenience of assembling of the parts we provide a groove 23 in 100 the plug 19 for the application of a screw driver. After the parts, however, are assembled and are to be adjusted delicately at any time, such adjustment may readily be effected through the open upper end of the 105 chuck socket only.

We claim:

1. In a button holding chuck, the com-

bination with a spindle having a threaded bore and an open topped chuck socket, of an abutment having a head located in said socket and a stem having threaded engagement in said bore, and means accessible through the open topped chuck socket to adjust the abutment and lock the same in adjusted position.

- 5 2. The herein described button holding
10 chuck comprising a spindle, an open topped chuck at the upper end of the spindle, said spindle having a threaded bore, of an abutment member having a head located in the
15 socket and an externally threaded stem co-
operating with the threaded bore, and means extending through the stem and accessible from the chuck end of the spindle for locking the abutment member for movement with respect to the chuck and spindle.
- 20 3. In a button holding chuck, the combination with a hollow spindle, an abutment member within the spindle and adjustable longitudinally thereof, and a locking device coöperating with the abutment member and
25 spindle and accessible through the top of the spindle for locking the abutment member from endwise movement with respect to the spindle.
- 30 4. A button holding chuck, the combination with a spindle having a threaded bore and a threaded counterbore at its lower end, of an abutment member having a head and a quill integral therewith, said quill having an external screw thread coöperating with
35 the threaded bore of the spindle, and a locking member comprising a plug coöperating with the threaded counterbore aforesaid and adapted to abut against the end of the abutment member quill, said locking member
40 also including a stem extending upward through the quill and accessible for manipulation through the abutment head.

5. In a button holding chuck, the combination of a spindle having an open topped

socket at one end and an internal screw 45
thread at its opposite end, an abutment member comprising a head within said socket and a quill projecting downward toward said threaded end of the spindle, and a locking member for the abutment member 50 comprising a threaded plug coöperating with the spindle thread aforesaid and adapted to abut against the adjacent end of the quill, said locking member including also a stem extending along the quill and accessible 55 through the open top socket for manipulation.

6. In a button holding chuck, the combination of a spindle, an abutment member therein having a head at one end and a 60 quill, the end of the quill opposite the head being longitudinally split, and a locking wedge member comprising a plug and an integral stem, the plug being tapered and coöperating with the split end of the quill to 65 spread the parts thereof apart and the stem projecting upward through the quill for manipulation thereof through the socket and abutment head, substantially as set forth.

7. The herein described button holding 70 chuck comprising a spindle having an internal thread and threaded counterbore, an abutment member including a head at one end and a quill projecting therefrom and having the opposite end of the quill externally threaded and longitudinally split, said threaded split end coöperating with the threaded bore of the spindle, and a locking member for the abutment member comprising an externally threaded plug coöperating 75 with the counterbore thread aforesaid and an integral stem projecting through the quill and accessible for rotation through the abutment member at the end remote from the plug.
